UNITED STATES PATENT OFFICE.

WILLIAM DEGENER, JR., OF NEW YORK, N. Y.

FREEZING APPARATUS.

No. 921,370.

Specification of Letters Patent.

Patented May 11, 1909.

Application filed April 1, 1908. Serial No. 424,489.

To all whom it may concern:

Be it known that I, WILLIAM DEGENER, Jr., a citizen of the United States, and a resident of the city of New York, borough of 5 Manhattan, in the county and State of New York, have invented a new and Improved Freezing Apparatus, of which the following is a full, clear, and exact description.

This invention relates to freezing apparatus, and more particularly to apparatus of 10 this kind in which the congealing of liquids by means of cold can be effected, and which includes means controlled by the change of volume of the liquids, due to the congelation, for operating the apparatus to discharge the congealed liquid and replace it with uncongealed liquid.

An object of the invention is to provide a simple, strong and durable freezing apparatus 20 which is efficient in operation and inexpensive to manufacture, and with which the ordinary cold of winter can be employed, or with which artificially induced low temperatures can be used for the production of ice 25 and other congealed liquids.

Another object of the invention is to provide a device of the class described, which is absolutely automatic in operation, by means of which receptacles of ice can be removed from the outer air, in which the freezing 30 is effected to a point within a house, an ice-box or the like, and which effects the removal of the receptacles to the outer air when the ice therein has melted.

A still further object of the invention is to provide a freezing apparatus which obviates the necessity of cutting ice on ponds and the like, by means of which the freezing of the water in blocks of predetermined shape can 40 be effected, and which are discharged automatically when the freezing is completed.

The invention consists in the construction, and combination of parts to be more fully described hereinafter, and particularly set 45 forth in the claims.

Reference is to be had to the accompanying drawings forming a part of this specification, in which similar characters of reference indicate corresponding parts in all the views, 50 and in which—

Figure 1 is a longitudinal section of my invention, showing a receptacle filled with liquid to be congealed, and a magazine of similar receptacles; Fig. 2 is a similar view 55 showing a receptacle filled with ice and about to be received from the outer air to within a

building; Fig. 3 is a transverse section showing the magazine of receptacles together with a track upon which the receptacles travel; Fig. 4 is a vertical section of a form 60 of my invention used upon lakes, ponds or the like, which obviates the cutting of ice, and which serves to effect the forming of ice in blocks, and the automatic discharge of the blocks; Fig. 5 is a longitudinal section 65 showing a modified form of my invention in which the receptacles or canisters of ice are discharged directly to an ice-box, and when the ice has melted are returned automatically to the outer air so that the contents 70 thereof can again be congealed; and Fig. 6 is a transverse section showing a portion of the ice-box and the means for returning the receptacles to the outer air.

Before proceeding to a more detailed explanation of my invention, it should be clearly understood that while I have shown for example, forms of the device which make use of the temperature of the atmosphere alone, for freezing the water, artificially induced low temperatures can of course be used equally well; for example, during those seasons of the year when the temperature of the air is normally too high for the congelation of water or other liquids. Water, 85 in freezing expands approximately one-eighth of its volume, and in thus expanding exerts a tremendous force. I make use of this force by means of suitable mechanism, for removing the congealed water to a place, 90 for example an ice-box, which is remote from the point of its congelation. In the form of the device used in connection with ponds, lakes and the like, to avoid the necessity of cutting ice, the expansive force of the 95 freezing water is used to discharge the blocks of ice formed, to a point adjacent to the device, from which they can be gathered by means of a vehicle or the like. I wish to emphasize that my invention resides not in 100 any of the various details of construction shown, for example, in the accompanying drawings, but consists primarily in the provision of means for utilizing the force developed by the expansion of a congealed 105 liquid, to remove the liquid when congealed, to a point at which it can be utilized, or to remove it merely, so that its place can be taken by other liquid to be congealed.

Referring more particularly to the drawings, 10 represents a window frame of a house or other building, provided with a window

11, which can be of the usual construction. While the form of my invention described below is shown as extending through the window of a building, it can equally well be 5 used in connection with some other opening in the wall of the structure. I provide track members 12 extending from the inside to the outside of the building, through the window opening, and resting upon the window sill 13. The track members 12 are separated and carry therebetween rollers 14 for a purpose which will appear hereinafter. At the outer ends of the track formed by the track members, is a back or stop 15 upon 10 which is securely mounted a helical spring 16. At the inner end of the track is a chute or run-way 17.

I prefer to use receptacles or canisters 18 substantially cylindrical in form and fashioned from sheet metal or other suitable material. The receptacles 18 have telescoping covers 19 which fit tightly thereupon to prevent leakage of the water 20 or other liquid which the receptacles contain. A receptacle 18 filled with water is placed upon the track rollers with one end engaging at a head 21 carried at the free end of the spring. At a point removed from the head 21 a distance substantially equal to the length of a receptacle 18 is a catch 22 slidably mounted 25 in a socket 23 carried upon one of the track members 12, and adapted to engage the receptacle to hold it in position. A spring 24 within the socket 23 normally projects the catch. The latter has a stud 25 which 30 engages a slot 26 of a bell crank lever 27 pivoted upon one of the track members 12 and connected with the head 21 by means of an arm 28 slidably mounted in a guide 29. The window opening is closed by means of a 35 flap 30 of suitable flexible material which can be displaced by the receptacle as the latter travels along the track upon the rollers.

As the liquid within the receptacle freezes 40 or congeals, it expands, and in expanding, the telescoping parts of the receptacle are forced apart, as is shown most clearly in Fig. 2. As the receptacle is held in position by the catch 22 the expansion of the liquid 45 compresses the spring 16. The head 21 moves with the spring, and through the arm 28 operates the bell crank lever 27. Consequently, when the liquid is congealed the 50 spring has been compressed to such a point that the catch is displaced to release the receptacle, and the potential energy stored in the spring, as the catch is released projects the receptacle along the track and into the building.

Adjacent to the track within the building 55 is a chute or magazine 31 in which is arranged a plurality of receptacles 18. The magazine has an outlet adjacent to the track, and a trigger 32 which holds the outermost receptacle 18 in place. The trigger 32

is mounted upon a pintle 33 pivotally carried by the track and having a rigid dog 34 together with an arm 35 carrying a weight 36 which tends to hold the dog in a normally upright position. As the receptacle 18 70 passes along the track from the outside air, it depresses the dog, and when it passes from the track, thus releases the first of the receptacles 18 within the magazine. The same rolls out upon the track and starts downward along it. The track, it will be understood, is suitably inclined for the purpose. The new receptacle then moves downward to the spring, and as soon as it passes from the dog 34 the trigger 32 is released, and in 75 time to engage the next of the receptacles in the magazine to hold it in position and prevent it from leaving the magazine. The receptacle moving downward upon the track passes over the catch 22, depressing the latter, which is suitably beveled to permit the passage toward the spring of the receptacle 18. If the outer air is cold enough, the liquid within the receptacles will be frozen. These will be successively discharged from 80 the magazine, and subsequently, when frozen, will be returned to the building, passing down the chute 17 to the point where they are to be utilized.

In Fig. 4 is shown a modified form of my 85 invention, which can be used as a substitute, for the operation of cutting ice upon ponds, lakes, reservoirs and the like. In this form of the invention I employ a substantially cylindrical casing 50 which is arranged in a 90 suitably formed opening in the ice A of a lake or pond B. The upper rim of the casing 50 projects above the surface of the ice A, while the lower part extends into the water of the lake B. A lid 51 is mounted at the upper 95 edge of the casing by means of a suitable hinge 52. A catch 53, pivoted at the side of the casing upon a suitable bracket 54 and arranged within a tubular chamber 55 at the side of the casing, serves to engage at the 100 edge of the lid 51 to hold the latter in a closed position. A piston or plunger 56 is slid- 105 able within the casing and has a piston ring 57 which insures a tight fit. The piston 56 has a hollow piston rod 58, sliding in a suitable opening 59 of the bottom of the casing, and provided with an annular lateral flange 60 which limits the movement of the piston longitudinally of the casing in one direction. A helical spring 61 incased in an envelop 62 110 of rubber or the like, surrounds the piston rod. The casing can be held by a float or in any other convenient manner before the lake freezes, and the ice then allowed to form 115 about the casing to secure it in position.

The chamber 55 extends longitudinally of the casing to a point below the piston and communicates with the casing underneath the piston by means of a slot 63 in the wall of the casing. A member 64 is arranged under- 120

neath the piston and has a stem 65 slidably located in the slot 63 and extending into the chamber 55. The stem 65 is joined by means of a line or link 66 with an arm 67 of 5 the catch 53. A flap 68, of flexible or other suitable material, closes the upper opening of the hollow piston rod 59 and constitutes a one-way valve. The envelop 62 serves to protect the spring 61 from the water which 10 might penetrate the casing underneath the piston. When the casing is filled with water and the lid 51 is closed and held closed by the catch 53, the expansion of the liquid within the casing, due to its congelation, forces the 15 piston downward and compresses the spring 61 until the piston engages the member 64 which is thereby operated to release the catch. The lid then flies open and the spring forces the ice from the casing. A leaf spring 20 69, mounted at the side of the casing within the chamber 55, engages the arm 67 and tends to hold the catch 53 in a normally operative position. A leaf spring 70, mounted at the opposite end of the casing and extending 25 upwardly above the same, is arranged to engage the lid 51 as the latter is swung to an open position, and returns it to a closed position after the ice leaves the casing.

As the ice is forced outward by the action 30 of the spring, the water from the lake enters the casing through the hollow piston rod 59, the valve 68 opening inwardly for this purpose. A vacuum is created by the movement of the ice from the casing and this acts 35 to draw water into the latter to the upper rim thereof. In this way the operation of the device is continuous, and as soon as one block of ice is formed and ejected the casing is filled with water, which subsequently 40 freezes to form a second block. If necessary, the casing can be greased or otherwise lubricated on the inner surface, to facilitate the removal of the ice blocks therefrom.

In the form of my invention shown in Figs. 45 5 and 6, a track 37 leads directly through a suitable opening 38 in a wall, into an ice chest, refrigerator or the like, 39, the opposite walls 40 of which are inclined toward each other from top to bottom. A return track 50 41 leads from the bottom of the refrigerator 39 through a suitable opening 42 to the outer end of the track at which the receptacles are positioned during the congelation. The receptacles filled with the congealed liquid enter the ice chest through the opening 38 in the upper part of the refrigerator and gradually move downward between the walls as the congealed liquid is melted in cooling. In this way the receptacles are gradually telescoped again and are ready to be returned to 60 the outer air to be again frozen. The part 43 of the refrigerator, within which the receptacles are located, constitutes a magazine having an outlet adjacent to the return track 65 41. A guide socket 44 is provided at the

outlet, in which is located a movable finger 45 held in a projected operative position by means of a spring 46. The trigger is connected by a line 47, passing over a pulley 48, with the bell crank lever 27, so that as the 70 receptacle at the outer end of the track is released, the lowermost of the receptacles within the refrigerator is released simultaneously therewith. A swinging trap 49 directs the receptacle moving under the impulse of 75 the spring 16 on to the upper track 37 and into the upper portion of the refrigerator. The trap 49 permits the released receptacle to move along the lower track 41 from the refrigerator to a position at the outer end of 80 the track, where it is to be congealed and from which it is subsequently returned to the refrigerator by the spring 16. The lower track 41 has rollers 14 and is suitably inclined to permit the return from the refrigerator of the successive receptacles filled 85 with liquid to be congealed.

Having thus described my invention, I claim as new, and desire to secure by Letters Patent:

1. In apparatus of the class described, a container for a substance to be congealed, a spring, and a movable member controlled by the substance and controlling said spring so that the spring is compressed by the substance in changing form when congealed, whereby said spring serves to advance the substance to a point remote from the point of its congelation:

2. In apparatus of the class described, means for converting the expansive force exerted by a congealing substance into potential energy, and means for utilizing the potential energy to remove the congealed substance to a point remote from the point of its congelation.

3. In apparatus of the class described, a container for a fluid to be congealed, and means controlled by the change in the volume of the congealing fluid, for removing the congealed fluid from the place of its congelation.

4. In apparatus of the class described, an adjustable container for a fluid to be congealed, means for converting the movement of the container due to the expansive force exerted by the congealing substance, into potential energy, and means for utilizing the potential energy to remove the container to a place remote from the place of the congelation of the fluid.

5. In apparatus of the class described, a container for a fluid to be congealed, means for resisting the expansion of the fluid while it is congealing, means for storing the force exerted by the expansion of the fluid, and means for utilizing the stored force to remove the congealed fluid.

6. In apparatus of the class described, a container for a fluid to be congealed, means for positioning said container at a point hav-

90

95

100

110

115

120

125

130

ing a temperature adapted to congeal the fluid, means for storing the energy produced by the change in volume of the congealing fluid, and means for utilizing the stored 5 energy to remove said container to a point remote from the first point.

7. In apparatus of the class described, a telescopic container for a fluid to be congealed, means for holding said container in 10 position at a point having a temperature adapted to congeal the fluid, means for storing the energy produced by the change in volume of the congealing fluid, and means controlled by said last-mentioned means, for 15 releasing said container.

8. In apparatus of the class described, a track, an extensible container for a fluid to be congealed, a stop for holding said container against movement along said track in 20 one direction, a spring engaging said container when the same is held in position upon said track, and a release controlled by said spring, for releasing said container.

9. In apparatus of the class described, a 25 track connecting two points having different temperatures, telescoping containers for a fluid to be congealed, a spring adjacent to said track at the point of lower temperature, means for holding a container in engagement

with said spring, means for releasing the container, a magazine for containers at the point of higher temperature, and means operable by the movement of a container along said track, for releasing one of the containers within said magazine, said track being inclined to permit a receptacle to travel gravitationally along the same from said magazine to said spring. 30 35

10. In apparatus of the class described, a track having at one end a spring, telescoping 40 containers for fluid to be congealed, means for holding one of said containers in engagement with said spring, means controlled by said spring for releasing one of said containers from its position against said spring, a casing 45 adapted to receive said receptacles at the upper end thereof, said track leading to the upper end of said casing, said casing being formed to telescope said containers as the same pass through said casing, and a return 50 track leading from said casing to said spring.

In testimony whereof I have signed my name to this specification in the presence of two subscribing witnesses.
